Machinery Corporation, Paterson, N. J., a cor-
poration of New Jersey

Application September 12, 1933, Serial No. 689,097
In Great Britain October 21, 1932

20 Claims. (Cl. 12—6)

This invention is concerned with improvements in or relating to shoe sewing machines and has particular reference to inseam sewing machines such as are used in the manufacture of 5 welted shoes or turn shoes.

In the application for United States Patent Serial No. 325,839, filed December 13, 1928, on which has been granted Patent No. 1,966,479, July 17, 1934, there is disclosed an inseam sewing 10 machine having a gripper device which acts to seize successively marginal portions of the upper of a shoe on a last and to pull the said portions heightwise of the last and inwardly over an insole on the last bottom, the said gripper moving, 15 as it exerts its pull on a marginal portion of the upper, towards the needle from a position spaced to one side thereof in order that the portion of the upper which it grips shall be sewn to the insole lip while it is actually held under tension close to the needle by the gripper and to assist a channel guide of the machine to feed the work step by step through the machine.

The gripper device disclosed in said prior application has been found in practice to operate 20 very satisfactorily but nevertheless has shown itself capable of improvement in various ways. For example the mechanism disclosed in the said prior application for imparting to the gripper its upper-pulling movements was found to be 25 somewhat cumbersome and the mechanism for opening and closing the gripper jaws was found not to offer convenient adjustment for regulating the extent to which the gripper jaws opened and closed in accordance with the thickness of 30 the upper materials of different shoes.

In the machine disclosed in the said prior application a ratchet wheel and eccentric device is provided for causing the gripper to be raised to and maintained in such a position when working 35 around the toe end of a shoe, the toe and heel end portions of the upper of which have already been lasted over the last and the end portion of which has been trimmed approximately to the height of the insole lip before the shoe 40 is presented to the inseam sewing machine, that it cannot descend far enough to abut against the upper materials around the toe end and cannot therefore hinder the smooth progress of the 45 inseam sewing operation around this portion of the shoe. With the arrangement described in the prior application however the gripper is lowered into its operative position to grip a portion of the upper materials just toeward of the heel 50 breast line immediately the sewing operation commences on a shoe and if the gripper is ac-

tually able to grip the upper in this locality (i. e. if the marginal portion of the upper is sufficiently upstanding in this locality to enable the gripper to seize it) there arises a danger that the heightwise tension away from the insole exerted on the upper by the gripper may lift the lasting tacks, which were inserted during the prior heel seat lasting operation to hold the heel end of the upper in lasted position close to the heel breast line, away from the insole and thus 10 disturb to some extent the position of the already lasted upper heelward of the position where the sewing operation commences. A similar danger exists when the combined sewing and lasting operation is drawing to a conclusion 15 along the opposite side of the shoe close to the heel breast line.

The objects of the present invention are to improve the construction and operation of the gripper device disclosed in the prior application 20 in a manner to overcome the above and other disadvantages and to render the gripper device more compact and more readily adjustable.

In an illustrative embodiment of the present invention hereinafter described a shoe-upper 25 gripper similar to that disclosed in the said prior application has its upper tensioning movements imparted to it through a short swinging lever which is coupled to an eccentric which also serves to actuate a ratchet and cam device by which the 30 gripper is rendered inoperative while working around the toe end of a shoe and is also prevented from moving from an inoperative position into upper-seizing position when the inseam sewing operation on a shoe is commenced in the waist of 35 the shoe on one side until a predetermined number of stitches have been made and the heel breast line of the shoe has been fed so far away from the position of the gripper in the machine that there will be little or no tendency for the gripper, 40 when it comes into operation and exerts a heightwise pull on the upper, to disturb the position of the already lasted heel seat portion of the upper on that side of the shoe. The said ratchet and cam device also serves to lift the gripper to and 45 retain it in an inoperative position at a predetermined time before the sewing reaches the heel breast line on the second side of the shoe so that the gripper shall not seize the upper close to the heel breast line on the second side of the shoe 50 and therefore disturb the position of the already lasted heel seat portion of the upper at that side. As hereinafter described the said ratchet and cam device is adjustable so that the precise time at which the gripper is allowed to come into oper- 55

ation on the upper when starting sewing may be varied to suit varying conditions in the work. Further in the same illustrative embodiment means are provided whereby the operator can accurately re-position (i. e. re-time) the said ratchet and cam device to cause the gripper to be lifted out of operative position at the correct time if he has to repeat the sewing operation along a part of the shoe, due for example to a 10 thread breakage after starting sewing and before the toe end is reached.

In order that the present invention may be more fully understood and its several features appreciated the illustrative embodiment aforementioned will now be described with reference to the accompanying drawings.

In the drawings,

Figure 1 is a right hand side elevation of the head of the illustrative embodiment;

Figure 2 is a right hand side elevation of certain parts seen in Figure 1.

Figure 3 is a front elevation showing part of the head;

Figure 4 is a right hand side elevation of certain parts seen in Figure 1;

Figure 5 is a right hand side elevation, on an enlarged scale of certain parts of the illustrative embodiment; and

Figure 6 is an isometric view of certain parts seen in Figure 5.

The said illustrative embodiment will be considered as embodied in an inseam sewing machine which, except that it has no work-piercing awl, is generally similar to that described in United States Letters Patent to Eppler, No. 1,108,560 granted August 25, 1914. The illustrative machine will be considered as being arranged to operate on welted shoes, the toe and heel end portions of which have previously been lasted prior to their presentation to the machine and the upper materials of which around the toe end have been trimmed away substantially to the height of the insole lip on the insole. The machine comprises a curved hooked needle 1, a looper 3, (Figure 3), a take up 5 and other instrumentalities which co-operate in a well known manner to form the stitches of a chain-stitch seam and is further provided, as is the machine disclosed in the application aforementioned, with a lasting 45 gripper indicated generally at 7 (similar in construction and function to that described in that specification) which is adapted to operate in time relation to the sewing instrumentalities to last side portions of a shoe upper before the said portions of the upper and welt are sewn by the machine to the insole. The lasting gripper is positioned to the right of the needle looking at the machine from the front as shown in Figure 3 and is supported at its upper end in a ball joint in the forward end of an updraw lever 9 which is pivoted on a horizontal and laterally extending stud 11 secured on a fixed portion of the machine frame and which is curved laterally between its pivot 11 and its forward end towards the needle position to allow the jaws 13, 15 at the lower end of the gripper to lie closer to the sewing point than they otherwise would. As is also the case in the gripper arrangement disclosed in the prior specification last mentioned the jaws of the gripper are likewise curved towards the needle, looking at the machine from the front, for a similar purpose.

The updraw lever 9 of the present illustrative embodiment is considerably shorter than that referred to in Patent No. 1,966,479 and the means

for imparting to it its falling and rising movements to cause the gripper to descend towards and to rise away from the shoe are somewhat different from those described for operating the updraw lever referred to in that specification.

The rear end of the updraw lever 9 of the present illustrative embodiment has freely pivoted in it a horizontal pin 17 which has secured upon its right hand end close against the right hand side of the lever 9 a short downwardly and rearwardly extending sleeve 19. A downwardly and rearwardly extending updraw rod 21 passes through the said sleeve 19 its upper end having pinned to it just above the said sleeve a hand nut 23 by which the rod may be rotated. The downwardly and rearwardly extending sleeve 19 has a second and rotatable sleeve member 25 threaded on to its lower end through which the updraw rod 21 also passes and a spring 27 resting at its lower end on the lower end of the second sleeve member 25 encircles the updraw rod and bears at its upper end against a collar fixed to the updraw rod. The sleeve member 25 and the spring 27 thus provide adjustable means whereby downward movement of the rod 21 imparts yielding 25 updraw movement to the gripper.

The lower end of the said updraw rod 21 is threaded into the upper end of a short coupling member 29 (see also Figure 5) lying coaxial with the rod and adjustably connected at its lower end with a bifurcated lever 31 freely mounted on a transversely extending shaft 33 and arranged to be rocked by an eccentric 35 on the main shaft 37 of the machine (which extends from left to right i. e. transversely of the machine) in a manner hereinafter described. The connection between the bifurcated lever 31 and the eccentric 35 on the main shaft is such that although the eccentric can rock the bifurcated lever rearwardly positively a given amount to impart the desired updraw movement to the gripper, the bifurcated lever can be rocked still further by means hereinafter described to cause the gripper to rise to and be maintained in a higher inoperative position in spite of the action of the eccentric. For this purpose the eccentric strap 39 of the said eccentric 35 has a pair of parallel bores 41, 43 extending rearwardly in a boss 45 formed on it and in the bore 41 is secured a short rod 47 which enters into a bore 49 in a socket 51 which is connected at its outer end by a pivot 53, to the bifurcated lever 31. A second short rod 55 is threaded in the second bore 43 in the boss 45 and passes outwardly through a downwardly projecting lug 57 formed on the socket 51 which lug normally rests on a face of the boss 45. A spring 59 is located between a collar 61 on the outer end of the rod 55 and the lug 57 and urges the socket 51 towards the eccentric normally to maintain the lug 57 against the face on the boss 45. The adjustable connection between the said coupling member 29 and the bifurcated lever 31 comprises a transversely extending pin 63 extending through the lower end of the coupling member, the opposite ends of which pin extend through slots 65 in the bifurcated members of the bifurcated lever 31 which lie on opposite sides of the said coupling member. The said slots in the bifurcated member, although straight, are substantially tangential about the axis of the pin 17 in the rear end of the updraw lever 9 which has the sleeve 19 first mentioned secured to it and wing nuts 67 threaded upon the ends of the pin 63 which extends through the coupling member serve to clamp the coupling member to the bifurcated 75

- lever in any position to which it may have been 5 adjusted along the said slots. This adjustable connection between the coupling member and the bifurcated lever enables the extent of the gripper lifting stroke imparted to the updraw lever by the bifurcated lever, as the latter is rocked by its eccentric, to be varied by the operator to suit the varying abilities to stretch of the upper materials of different shoes.
- 10 A spring-pressed striker or abutment 68 (Figure 4) together with a threaded sleeve nut 69 for varying the compression of a spring 71 housed between a shoulder on the striker 68 and the lower end of the nut 69 are housed in an upwardly extending threaded sleeve 73 which is threaded into the forward end of a gripper closing lever 75 and which may be rotated to adjust the heightwise position of the lower face of the striker 68 with which the upper end of the jaw-closing rod or 15 plunger 77 is maintained in contact by springs 79. By varying the heightwise position of the striker 68, and therefore varying the heightwise position of the jaw-closing plunger 77, the extent to which the gripper jaws are allowed to open 20 when the striker rises and the extent to which they are closed when the striker descends may be varied to suit different thicknesses of upper materials. The jaw-closing plunger 77 is connected to the moving griper jaw 15 to cause it to move 25 forwardly towards the fixed jaw 13 by a link 81 the moving jaw being pivoted at 83 to the gripper as shown in Figure 2. The gripper jaw closing lever 75 of the present illustrative embodiment is similar to that referred to as 142 in Patent No. 1,966,479 30 and is pivoted at 85 on the updraw lever 9 and is connected at its rear end to the forward end of a cam-actuated lever 87 which is actuated to impart to the gripper jaws their closing movements in a manner similar to that described with reference 35 to the lever referred to as 154 in the prior patent. A manually adjustable connection is provided in the present illustrative embodiment between the gripper closing lever 75 and the said cam-actuated lever 87 to allow the gripper jaws to be opened 40 by the operator at any time after they have been closed upon the work and this adjustable connection is more compact and more easily operable than that described for the same purpose in Patent 45 No. 1,966,479. In the present illustrative example the connection between the rear end of the gripper closing lever and the said cam-actuated lever comprises a toggle having two short links 89 and 91 (see Fig. 4). The upper end of the link 89 is pivotally connected to the rear end of the gripper closing lever and the lower end of the link 91 is pivotally connected to the forward end of the cam-actuated lever 87. A rearwardly extending 50 spring 93 is connected to the link 91 and tends to straighten the toggle rearwardly. Co-operating shoulders 95, 97 are provided on the forward 55 sides of the toggle links 89, 91 and normally maintain the toggle links in straightened condition against the action of the said spring 93. The lower toggle link 91 has a curved handle 99 secured to it which extends upwardly and forwardly to a convenient position for the operator above the rear end of the gripper closing lever. By pulling the said handle forwardly the operator can break the toggle about its knuckle 101 in a 60 forward direction thus pulling down the rear end of the gripping closing lever 75 and allowing the gripper jaws to open under the action of the springs 79 which maintain the jaw closing plunger 77 in engagement with the striker 67.
- 65 In the machine disclosed in Patent No. 1,966,479
- aforesaid, a ratchet and eccentric device is provided for automatically lifting the gripper to and retain it in such an elevated position when sewing around the toe end of a shoe that the gripper cannot engage the upper materials around this portion. The said ratchet and eccentric device also operates to lower the gripper once more to operative position when the sewing around the toe end has been completed and is described in the said patent as being connected to the updraw 10 lever 70 of the gripper to control the gripper in the manner just described by a rocking lever 220 and a slotted link 104 of the application.
- 15 In the present illustrative embodiment a ratchet and cam device is substituted for the ratchet and eccentric device of the machine disclosed in Patent No. 1,966,479 and this ratchet and cam device acts as hereinafter described upon the bifurcated lever 31 to which the rear end of the updraw rod 20 25 is connected to rock the said bifurcated lever 20 rearwardly, to raise the gripper to such an elevated position when working around the toe end of the shoe that the gripper is prevented from engaging or abutting against the upper materials. The cam of the said ratchet and cam device also provides means whereby the gripper is, in the manner hereinafter described, prevented from coming into operative position to operate on a shoe at the commencement of the sewing operation until a predetermined number of stitches have been sewn 30 and may be lifted to an inoperative position just before the conclusion of the sewing operation.
- 35 The said ratchet and cam device comprises a ratchet wheel 103 secured to a rotatable and transversely extending shaft 105 mounted in fixed bearings below the level of the shaft 33 on which the bifurcated lever 31 is mounted and slightly forwardly of the latter. A substantially horizontal and forwardly and rearwardly extending lever 107 is freely pivoted on the ratchet wheel shaft 40 45 50 55 60 65 70 75 80 85 90 95 100 105 110 115 120 125 130 135 140 145 150 129 rigidly secured to it on its right hand side by a screw and slot connection (not shown) which allows the cam to be adjusted relatively to the ratchet wheel if necessary. This cam disc has 5 formed upon its edge a relatively large hump 131 the greater portion of which extends around the cam concentrically with the axis of the shaft 105 through about eighty degrees and a relatively small hump 133 positioned almost but not quite 10 diametrically opposite the large hump and extending around the cam also concentrically with the axis of the shaft 105 through some thirteen degrees. The said ratchet wheel has secured to its left hand face two small shrouding plates 135, 137 15 which are each of a width (considered around the periphery of the ratchet wheel) equal to the length of two of the teeth on the ratchet wheel and extend radially of the ratchet wheel with their outer edges lying on a level with the tops of the 20 teeth on the ratchet wheel to shroud adjacent teeth from the action of the pawl 115. One of the said plates i. e. the plate 135 lies opposite the rear end of the small hump 133 on the said cam (considered in the direction of rotation of the cam) and the other plate 137 lies about twenty 25 eight degrees behind the plate 135 also considered in the direction of rotation of the cam. Each plate serves at times and in the manner herein-after indicated to prevent rotation of the ratchet 30 wheel by the pawl 115. A small cam lever 139 is arranged to be actuated by the said cam disc 129 to raise the gripper to an inoperative position at the appropriate times and this cam lever is freely rotatable on the shaft 33 on which the bifurcated lever 31 is mounted. The small cam lever has a short forwardly extending arm which carries a cam roll 141 at its end which rests upon the periphery of the cam disc 129. A short upwardly extending arm 143 of the said lever 139 35 has secured to it by a slot and bolt connection an arm 145 which is also freely mounted on the shaft 33 and has a stop-face 147 formed on it at its rear with which stop-face a stud 149 on the forward side of the bifurcated lever 31 comes into 40 contact when the lever 31 has been swung forwardly by its eccentric 35 as far forwardly as possible. The pawl 121 which is carried by the rear end of the lever 107 is arranged to be maintained normally out of engagement with the ratchet wheel by a shielding plate 151 which lies 45 between the pawl and the ratchet wheel and abuts against the pawl. The said shielding plate comprises a thin blade-like member which is secured at its upper end to a laterally extending boss 50 projecting from the left hand side of a curved lever 153 which is freely pivoted on the shaft 105. The lever 153 is normally maintained in such a position that the shielding plate 151 maintains the pawl 121 out of contact with the ratchet 55 wheel by a trip rod 155 which extends downwardly through an opening in the end of the lever 153 and is coupled at its lower end to a bell crank lever which is arranged to be rocked about a transverse horizontal pivot by rearward movement 60 of a knee-operated push rod. A rearward movement of this push rod causes the trip rod 155 to rock the curved lever 153 carrying the shielding plate 151 in a counter-clockwise direction looked at from the right of the machine and thus to lift the shielding plate from between the said pawl and the ratchet wheel.

The action of the ratchet and cam device will now be described. When the machine is at rest the cam roll 141 on the small cam lever 139 is resting upon the small hump 133 on the cam disc

129 near the rear end of the hump considered in the direction of its rotation, the pawl 115 resting, as shown in Figures 5 and 6, out of contact with the ratchet teeth, on the outer edge of the small plate 137.

The fact that the cam roll 141 is resting at this time on the small hump causes the stop face 147 at the upper end of the arm 145 to occupy a rearward position in moving to which it will have swung the bifurcated lever 31 further rearwardly 10 than it could be moved by its eccentric 35 and thus will have moved the gripper to a position in which it is raised above the work so far that it cannot, until it has been allowed to descend, engage the upper of a shoe presented to the machine. The gripper jaws 13, 15 will also be closed at this time. The shielding plate 151 will at this time be maintaining the pawl 121 on the rear end of the lever 107 out of contact with the ratchet wheel, a spring 152 serving normally to swing 20 the rear end of the lever 153 downwardly for this purpose until a boss 154 on its lower portion is arrested by contact with a fixed face 156 on the machine. Before the operator commences the inseam sewing operation on a shoe, assumed to be 25 of average size, presented to the machine he urges the knee-operated push rod aforementioned rearwardly and thus swings the lever 153 against the action of the spring 152 to withdraw the shielding plate 151 upwardly thus allowing the pawl 121 to swing into engagement with the teeth on the ratchet wheel to be ready, when the lever 107 is rocked by the eccentric 35 on the main shaft, to move the ratchet wheel one step forwardly in a 35 clockwise direction looked at from the right of the machine to carry the small shrouding plate 137, on which the other pawl 115 carried by the lever 107 rests, upwardly away from beneath the said pawl to allow that pawl to become operative to 40 rotate the ratchet wheel in a step by step manner. When the operator has pushed the knee-operated push rod rearwardly and thus withdrawn the shielding plate 151 to an inoperative position it is retained, in said position until the pawl 121 at 45 the rear end of the lever 107 has actually rotated the ratchet wheel one step, by a spring tooth 157 carried by the lever 153 on which the shielding plate 151 is carried, which spring tooth 50 engages with the teeth on the ratchet wheel. As the ratchet wheel is rotated through one step after the shielding plate 151 has been withdrawn upwardly, the lever 153 which carries the shielding plate and spring tooth 157 is caused to rock downwardly in company with the ratchet wheel 55 (through the action of the spring 152) until the shielding plate is ready once more to abut against the pawl 121, as the latter is moved upwardly to its initial position after having moved the ratchet wheel through one step, to lift the 60 said pawl out of engagement with the ratchet wheel.

Having urged the said knee-operated push rod rearwardly the operator presents a shoe to the machine with its toe end pointing towards the right and the waist portion of the shoe near to the heel breast line opposite the needle 1 and after having positioned the channel guide 158 properly in the channel in the insole, then depresses the starting treadle of the machine. The inseam 65 sewing operation then commences and proceeds along the waist of the shoe towards the toe end. When the machine shaft has started to rotate, lever 107 which carries the pawls 115, 121 will be rocked upwardly and downwardly once in every 70 75

machine cycle and, since the shielding plate 151 will already have been withdrawn upwardly to an inoperative position by the knee-operated push rod, the first rocking movement of the lever 107 which takes place in a clockwise direction looked at from the right of the machine will cause the pawl 121 at the rear end of the lever to rotate the ratchet wheel one step in clockwise direction looked at from the right. As this occurs, the knee-operated push rod may be released and the shielding plate 151 once more descends to its operative position as above stated and separates the pawl 121 from the ratchet wheel as the lever 107 swings upwardly once more. As also hereinbefore stated the movement of the ratchet wheel imparted to it by the pawl 121 causes the shrouding plate 137 on which the pawl 115 on the lever 107 rests, to move upwardly away from beneath the pawl 115 and therefore allows the said pawl 20 to ride into engagement with the ratchet teeth to rotate the ratchet wheel on further swinging movement of the said lever 107. The position, in the stopping position of the machine, of the cam roll 141 on the small hump 133 of the cam 129 is such that, through the action of certain adjustable cam-roll controlling means hereinafter described, the roll will only have descended upon a lower concentric part of the cam when the machine has made a predetermined number (say 30 three) of stitches and the heel portion of the shoe has been moved by the channel guide 158 of the machine (which acts, as in the prior application referred to, as a work feeding member) away from the needle through a similar number 35 of stitch lengths. As the cam roll 141 descends from the small hump in the manner hereinafter described, the stop face 147 at the upper end of the upwardly extending arm 145 secured to the small cam lever 139 will move forwardly thus allowing the spring 59 which forms part of the connection between the eccentric strap 39 on the main shaft and the bifurcated lever 31 to which the updraw rod 21 is connected to urge the bifurcated lever forwardly to lower the gripper into 40 operative position. Immediately this has occurred the gripper (the jaws 13 and 15 of which are continuously opened and closed when the machine is in operation even when the gripper is in its raised inoperative position) commences to operate on the upstanding margin of the shoe upper and, prior to each advancing movement of the needle through the work, seizes a portion of the upper and exerts a pull on it heightwise of the shoe and inwardly over the insole on the last moving as it does so towards the needle to assist the channel guide to feed the work through the machine and to present the portion of the upper which it engages, still in tensioned condition, to the needle to be sewn thereby to the insole lip. 45 The gripper continues in operation operating prior to each stitch to pull a portion of the upper over the last in the manner described and the ratchet wheel continues to move in a stepwise manner at each cycle of the machine while the sewing operation continues along the side of the shoe towards the toe end thereof. When the end of the toe cap line on that side of the shoe approaches the needle (or when, in the case of a shoe having no toe cap, the position on the shoe 50 where the end of the toe cap line would lie if the shoe was a capped shoe approaches the needle) the large hump 131 on the cam comes beneath the cam roll 141 on the small cam lever 139 and once more rocks the latter in a clockwise direction looked at from the right and once more 55 causes the stop faces 147 at the upper end of the arm 145 to rock the bifurcated lever 31 rearwardly against the action of the spring 59 and thereby to raise the gripper once more to its inoperative position. The sewing operation 5 continues, while the cam roll 141 rides along the concentric portion of the large hump 131, the gripper being prevented from coming into contact with the work. As the sewing around the toe end 10 progresses the ratchet wheel 103 continues to move in a stepwise manner until after about fifteen or sixteen stitches have been made (when the stitching will have been carried out around the extreme toe end and is approaching the toe cap line on the opposite side of the shoe) the cam roll 141 starts to fall slowly along a gently sloping side of the large cam hump 131 towards a concentric portion thereof of smaller radius. As the cam roll rides down the said face during the 20 formation of successive stitches, near the tip line, the gripper is allowed (by the forward movement of the stop face 147) gradually to come into operation until, when the toe cap line position on the second side of the shoe has just been passed, the 25 gripper is once more fully in operation imparting its heightwise and inwardly directed pulls to the upper margin. The sewing continues along this side of the shoe towards the heel breast line and the ratchet wheel 103 and cam 129 continue to 30 rotate in a stepwise manner until about when the ball of the shoe (the term ball being herein used as meaning that region on either side of a shoe where the forepart merges into the waist) is reached the shrouding plate 135 on the ratchet 35 wheel which lies opposite the rear end of the small hump 133 on the cam 129 (considered in the direction of rotation of the latter) comes beneath the pawl 115 on the lever 107 and, since the pawl 121 on the rearwardly extending arm of the said 40 lever is maintained out of engagement with the ratchet teeth at this time by its shielding plate 151, no further rotation of the ratchet wheel and cam takes place for the time being. The cam roll 141 on the small cam lever 139 lies, when the 45 rotation of the cam ceases, close to the forward side of the small hump 133 on the cam and is ready, when the cam once more starts to rotate, to ride up the small cam hump and raise the gripper once more to its inoperative position. The 50 sewing along the second side of the shoe continues towards the heel breast line and when the sewing has proceeded to within about a predetermined number of stitch lengths from the point near the heel breast line where the sewing is to finish, the 55 operator urges the knee operated push rod rearwardly once more and thus withdraws the shielding plate 151 upwardly to allow the pawl 121 to engage the ratchet wheel. When this has been effected the next rotation of the eccentric 55 60 causes the ratchet wheel to rotate one step and thus to cause the small cam hump 133 to ride somewhat beneath the cam roll 141 on the small cam lever 139 and also thus to cause the gripper to be lifted once more somewhat towards its inoperative position while the sewing operation continues. The cam roll rides along the said hump and the gripper will be completely raised to its inoperative position as the ratchet wheel makes a further step and remains raised while as 65 the ratchet wheel makes three still further steps (and the machine therefore makes three still further stitches) and at the end of this time, while the cam roll is still resting on the small cam hump and the gripper is still raised in its inoper- 70 75

ative position the shrouding plate 137 on the ratchet disc which is spaced rearwardly away from the small hump on the cam (considered in the direction of rotation of the cam) will have 5 lifted the pawl 115 on the lever 107 out of engagement with the ratchet teeth and the ratchet wheel and cam therefore come to rest. If the sewing operation on the shoe has not concluded by this time it is continued while the gripper 10 remains inoperative and the machine comes to rest with the gripper still raised in its inoperative position and its jaws closed. Thus, as hereinbefore described, the machine is provided with means controlled by the operator whereby the gripper is 15 delayed from coming into operation to last a shoe until several stitches have first been sewn, is lifted out of operation while sewing around the toe end and may be lifted out of operation at an appropriate time before the sewing operation on 20 the shoe is concluded.

If the operator should desire for any reason to use the machine purely as an inseam sewing machine (for example if he desires to sew the inseam of a shoe which has been completely lasted prior 25 to its being presented to the machine) without allowing the gripper to exercise any lasting action on the shoe he can do so by omitting to urge the knee operated push rod rearwardly and thereby putting the ratchet driving means into operation.

30 The adjustable means aforesaid for controlling the time at which the cam roll 141 on the small cam lever 139 descends from the small hump 133 on the cam after commencing to sew a shoe comprises a depending latch arm 159 which is freely pivoted at its upper end on a horizontal pivot pin 161 which extends in a direction from left to right of the machine. Just above its lower end the latch arm is provided on its forward side with a forwardly projecting shoulder 163 which 35 is arranged, when the gripper is in its inoperative position, to engage the underside of a pin 165, of square section, which is formed as an extension of the pin on which the cam roll 141 of the small cam lever 139 is mounted. Thus the said latch arm prevents the cam roll from descending along the sloping side of the small hump to allow the gripper to come into operation until the latch arm has been swung away out of engagement with the pivot pin for the cam roll.

50 The said latch arm is spaced a short distance away from the right hand face of the cam and is provided along its lower end with a straight slot 167 which is tangential about the pivot pin 161 on which the arm is mounted. A horizontal pin 169 which extends through the slot 167 to a 55 position almost in contact with the right hand face of the cam 129 is adjustably clamped in the said slot in the latch arm by means of a collar formed on the pin on the left hand side of the arm and a nut 171 threaded on the right hand end of the pin on the right hand side of the arm. Two pins 173, 175 project horizontally from the right hand face of the cam 129 at substantially the same radial distance from the axis of the cam as the pin 169 and the said pins 173, 175 are of such 60 length that they come into contact, in turn, as the cam rotates with the forward face of the pin 169 and act to rock the latching arm rearwardly of the machine to release it from engagement with the pivot pin 165 for the cam roll 141 on the small cam lever 139. The two pins 173, 175 on the cam are arranged diametrically opposite each other, the one 173 being arranged somewhat rearward (considered in the direction of 65 rotation of the cam) of the rear end of the small

hump 133 on the cam and the other 175 being arranged somewhat forwardly of the rear end of the concentric face on the large hump 131 on the cam.

70 The pins 173, 175 on the cam 129 co-operate with the pin 169 on the lower end of the latch arm in a manner now to be described. When the machine is in its position of rest the shoulder 163 on the latch arm 159 will lie beneath, and in engagement with, the pin 165 of the cam roll 141 on the small cam lever 139 and the cam roll will, as hereinbefore stated, lie on the small cam hump 133 near to its rear end considered in the direction of rotation of the cam. Assuming the pin 169 at the lower end of the latch arm to be 75 secured in position at the forward end of the slot 167 (as shown in Figure 5) in the latch arm and the knee-operated push rod to have been urged rearwardly before the starting treadle of the machine is tripped, the ratchet wheel will start to 80 rotate in a stepwise manner as previously described immediately the sewing operation commences and the pin 173 which is secured to the cam just rearward of the small cam hump (considered in the direction of rotation of the cam) 85 will abut against the forward face of the pin 169 which is secured to the latch arm immediately the rotation of the ratchet and cam commences. After the ratchet wheel and cam have made three 90 stepwise movements in the manner described 95 the latch arm will have been rocked so far rearwardly by the pin 173 on the cam that it will release the cam roll 141 on the small cam lever 139 and the latter will therefore be swung downwardly by the spring 59 (the small cam hump 133 100 on the cam having already passed away from under the roll) to allow the gripper to descend into operative position to commence its lasting operations on the shoe. On continued rotation 105 of the cam 129 the pin 173 which abuts against 110 the pin 169 on the latch arm will have swung the latter so far rearwardly and upwardly that it can ride beneath the pin 169 on the latch arm 159 out of contact with it thus allowing the latch arm to be swung forwardly and downwardly by 115 a coil spring 177 ready for its shoulder 163 to engage beneath the pivot pin of the cam roll 141 when the cam roll has once more been lifted 120 sufficiently far by the cam 129. This will occur 125 when the large hump 131 on the cam comes beneath the roll to lift the gripper to its inoperative position as the sewing around the toe end of the shoe commences but the second pin 175 on the cam 129 will engage the pin 169 on the latch arm 130 before the sewing around the toe end is completed and will rock the latch arm rearwardly 135 once more to release the cam roll and allow it to ride gently down the rear face of the large hump (considered in the direction of rotation of the cam) without any restraining influence being 140 exercised on the cam roll by the latch arm at this time. By adjusting the pin 169 carried by the latch arm rearwardly along its slot 167 the time at which the latch arm will be rocked rearwardly away from engagement with the cam roll 141 just after the sewing operation on a shoe 145 has commenced to lower the gripper to operative position, can be delayed to enable a greater number of stitches (for example any number up to 150 nine) to be made along the waist of a shoe while the gripper is maintained out of operation. This possibility is found to be of considerable advantage when operating for example on shoes having heel end counters which extend further forwardly along the waist towards the toe end than usual 155

as it is desirable, in order to avoid the possibility of the gripper disturbing the position of the counter in the shoe, that the gripper should be delayed from coming into action until the sewing has progressed to a point toewardly of the toeward end of the counter. It will be appreciated that the latch arm arrangement just described operates only to delay the coming into operation of the gripper after the commencement 5 of the sewing operation on a shoe and does not play any part in controlling the time at which the gripper can be lifted out of operation before the sewing operation is concluded on a shoe. As however the operator can very clearly see the 10 progress of the operation of the machine as it continues along the second side of the waist towards the heel breast line and can by operating the knee-operated push rod at any time while sewing along the second side of the waist, ensure 15 that the gripper will be raised to its inoperative position after a further two stitches beyond the point where the rod is actuated have been made, he is well able to cause the gripper to rise to its inoperative position at any desired 20 period before the sewing operation reaches the heel breast line. A friction band device not shown is provided continually to grip the shaft 105 of the ratchet wheel and cam to prevent the ratchet wheel and cam from being rotated, by the action 25 of the cam roll as it rides down the rear end face of the large cam hump faster than its driving means operate it.

It occasionally happens when the inseam sewing operation on a shoe is being carried out by machine that the thread breaks before the sewing operation has been completed and the machine shaft makes several further revolutions before its movement can be stopped. As described above the ratchet wheel and cam device of the 30 illustrative machine is moved one step forward for each operation of the machine until the machine has sewn to about the ball on the second side of the shoe and therefore if, during the sewing up to this part of a shoe by the illustrative machine, the thread breaks for example while the sewing is proceeding along the first side of the shoe towards the tip line and the machine shaft makes several further rotations before it can be brought to rest, the ratchet wheel and cam device will by that time have made several 35 further steps forward beyond the position it occupied at the instant when the thread broke. Therefore when the shoe is once more presented to the machine for the sewing to recommence at the point in the shoe where the last complete 40 stitch was made the position of the large hump 131 on the cam will have been disturbed with regard to its relation to the progress of the sewing operation, and unless corrected, would in the particular case last referred to act to lift the gripper to its inoperative position at an incorrect time (i. e. earlier than it should) during the sewing operation. In the illustrative embodiment of 45 the present invention means is provided whereby the operator can readily reposition the ratchet wheel and cam device to its correct relation to the progress of the sewing operation if the thread in the machine has broken and the sewing operation is to be restarted on any portion of the shoe. 50 The said means comprises a chart in the form of a rotary disc 179 (see Figures 1 and 3) on which is outlined a pattern of a shoe bottom. The said disc is positioned in clear view of the operator to the right hand side of the machine and is fixed 55 to the forward end of a horizontal forwardly

and rearwardly extending shaft 181 which is mounted in fixed bearings in a bracket secured to the right hand side of the machine frame. The rear end of this shaft is coupled by bevel gears (not shown) to the transversely extending shaft 105 on which the ratchet wheel 133 is secured so that the disc rotates once in a counter-clockwise direction looked at from the front of the machine for every rotation of the ratchet wheel. The outline of the pattern of the shoe 60 bottom is so positioned on the disc that it lies horizontally across the disc with the toe end pointing towards the right when the machine is inoperative ready for a shoe to be offered to it. In Figures 1 and 3 the machine is shown in a 65 position which it would occupy after about four stitches have been made after the commencement of the sewing operation. A line 183 on the said disc runs from a point in the waist of the pattern close to the position where the heel breast line would lie (and corresponding to the position on the shoe at which the sewing would commence) to the periphery of the disc at the left hand side of the latter when the machine is inoperative ready for a shoe to be presented 70 to it and a fixed indicating pointer 185 lies opposite the periphery of the disc. Thirty-two other lines are drawn as seen in Figure 3 from points spaced apart around the pattern forwardly of the heel breast line to points spaced equally apart 75 around the periphery of the disc which latter points lie in turn opposite the said pointer 185 when the sewing is being carried out on parts of the shoe corresponding to those on the pattern from which the lines are respectively drawn. 80 Thus, for example, when the sewing has proceeded say to a point on the shoe close to the ball, the disc will have been rotated by the ratchet wheel shaft so far that a line 187 on the disc leading to the periphery of the disc from 85 the corresponding point close to the ball on the pattern lies opposite the pointer 185 and when the sewing operation has reached the extreme toe end of the shoe a line 189 leading from the extreme toe end of the pattern to the periphery of 90 the disc will lie opposite the pointer 185. If therefore the thread in the machine should break when the sewing has, for example, reached the extreme toe end of the shoe and the machine has run on somewhat further before it is brought 95 to rest, the operator can, by rotating a hand wheel 191 secured to the right hand end of the shaft 105 on which the ratchet wheel is secured after the machine has come to rest, rotate the ratchet wheel and cam through almost a complete revolution in the direction in which the ratchet wheel is normally rotated until the line 100 189 leading from the toe end of the pattern to the periphery of the disc lies once more opposite the pointer 185. Thereafter he can recommence 105 the sewing of the shoe at the extreme toe end with the certain knowledge that the cam humps 131 and 133 on the cam which is secured to the ratchet wheel will be correctly "timed" in relation to the progress of the sewing operation. As 110 has already been described the ratchet wheel remains stationary while the sewing is progressing from about the ball of the shoe on the second side until the operator pushes rearwardly the knee operated push rod just before the sewing operation finishes and therefore no lines are drawn on the said disc leading from points between the ball of the shoe and a position somewhat forward of the heel breast line on that side of the 115 120 125 130 135 140 145 150 155 160 165 170 175 180 185 190 195 200 205 210 215 220 225 230 235 240 245 250 255 260 265 270 275 280 285 290 295 300 305 310 315 pattern which represents the side last to be sewn in the shoe.

Since the ratchet wheel 103 aforesaid is rotated one step for each rotation of the machine 5 shaft and the cam 129 which is secured to the ratchet wheel and the chart-disc 179 are also therefore rotated one step for each rotation of the machine shaft it might seem necessary that the ratchet wheel should have a number of teeth 10 which is determined in accordance with the number of stitches to be sewn around the particular shoe to be operated upon and that the exact locations of the humps 131, 133 on the cam 129 should be determined by the number of teeth on the 15 ratchet wheel.

In the use of the illustrative machine however it is found that, since the work feeding instrumentalities of the machine comprise only the channel guide 158 which engages the work in a 20 non-positive manner and the gripper 7 which engages only the upper materials extending freely from the margin of the shoe bottom, the distance the work is fed between successive stitches (and therefore the number of stitches made around a 25 shoe) may be determined largely by the feeding effort exerted on the work by the operator. It is consequently found that in practice when using the illustrative machine the number of stitches made around a shoe of average size, at least along 30 the sides thereof, as a rule differs but slightly from that made when working on a larger shoe and therefore a ratchet wheel having a given number of teeth and a cam on which the humps are disposed at predetermined distances apart 35 may be used to operate with substantially equal efficiency on a relatively wide range of shoes. The same consideration applies in the case of the chart disc.

In the machine described in Patent No. 1,966,479 40 a swinging finger referred to as 170 is provided for urging a portion of the upper inwardly over the margin of the insole before the gripper seizes the said portion to tension it heightwise of the last and over the margin of the insole. In the 45 present illustrative embodiment however instead of making use of such a finger there is provided for a similar purpose on the forward end of the usual welt guide 193 a forwardly projecting rib 194 which extends substantially horizontally 50 across the welt guide and is turned downwardly somewhat at its forward end. The welt guide, as is usual in machines of the type disclosed in the before mentioned patent to Eppler, No. 1,108,560, is advanced forwardly to press against the work 55 near the edge of the insole just before the needle makes its work-penetrating stroke and the said rib on its forward end serves, as the welt guide advances, to urge the portion of the upper which is held under tension by the gripper at that time inwardly over the edge of the insole and downwardly towards the margin of the insole and towards the angle between the root of the insole lip and the body of the insole thus exercising an additional lasting effect on the upper and assisting 60 the gripper in holding the upper in the best position 65 for the sewing operation.

In the gripper arrangement disclosed in Patent No. 1,966,479 the position of the gripper jaws forwardly and rearwardly of the machine may be 70 adjusted by rotation of a threaded sleeve 126 of said application which forms a support for the lower end of the gripper and is mounted on a forwardly and rearwardly extending stud 122 which reciprocates with the feed slide of the machine and can rise and fall in a vertical plane as

the gripper receives its upward and downward movements. In the present illustrative embodiment the arrangement for supporting the lower end of the gripper is somewhat different from that described in the prior specification last mentioned. In the present illustrative embodiment the gripper is embraced at its lower end by a fork 195 which extends rearwardly and upwardly and is connected at its forward end to the gripper by the pin 83 which forms the pivot pin on which the movable gripper jaw 15 moves towards and away from the fixed gripper jaw. The fork has a cylindrical stem 197 extending rearwardly from it which passes through a sleeve member 199, a shoulder on the forward end of the stem and nut 201 on its rear end serving to hold the stem against endwise movement in the sleeve member. The said sleeve member is pivotally mounted, above the stem, on a short shaft 203 which reciprocates with the feed slide 205 of the machine and extends from left to right of the machine and the sleeve member 199 moves with the said shaft 203 in its reciprocations to impart the work feeding movements to the gripper. The sleeve and stem can therefore rock upwardly and downwardly 25 about the short shaft 203 in accordance with the rising and falling movements of the gripper. The said short shaft 203 can be rotated by a hand piece 207 at its right hand end and the portion of the shaft on which the sleeve member 199 is 30 mounted is formed eccentrically of the axis of the shaft so that by rotating the shaft the lower end of the gripper can readily be adjusted forwardly and rearwardly of the machine to suit the special conditions called for by shoes of different kinds. A friction device not shown may be provided to maintain the short shaft in any angular position to which it may have been adjusted.

Having thus described an embodiment of the 40 invention, what is claimed is:

1. A shoe machine having in combination, 45 mechanism for progressively securing successive portions of a shoe upper and a sole together, an upper tensioning gripper acting in time with the securing mechanism to seize successive portions of the shoe upper preparatory to each securing operation and means driven by the securing mechanism to prevent the gripper from seizing the upper during a predetermined number of 50 successive operations of the securing mechanism adjacent the heel end of shoe and to cause the gripper to be rendered operative along other portions of the shoe.

2. A shoe machine having in combination, 55 mechanism for progressively securing successive portions of a shoe upper and a sole together, an upper tensioning gripper acting in time with the securing mechanism to seize successive portions of the shoe upper preparatory to each securing 60 operation and means driven by the securing mechanism to prevent the gripper from seizing the upper during the first operations of the securing mechanism on a new shoe and to cause the gripper to be rendered operative during other 65 operations thereafter.

3. A shoe machine having in combination, 70 mechanism for progressively securing successive portions of a shoe upper and a sole together, an upper tensioning gripper acting in time with the securing mechanism to seize successive portions of the shoe upper preparatory to each securing operation and means driven by the securing mechanism to cause the gripper to be rendered operative along certain portions of the shoe and 75.

to be prevented from seizing the upper during the final operations of the securing mechanism on the shoe.

4. A shoe machine having in combination, 5 mechanism for progressively securing successive portions of a shoe upper and a sole together, an upper tensioning gripper acting in time with the securing mechanism to seize successive portions 10 of the shoe upper preparatory to each securing operation and means driven by the securing mechanism to prevent the gripper from seizing the upper during the first and final operations of the securing mechanism on a shoe and to render the gripper operative during operations of the 15 securing mechanism between the times when the gripper is inoperative.

5. A shoe lasting and sewing machine having in combination, upper tensioning means, sewing mechanism for securing a shoe upper and a sole 20 together, means driven by the sewing mechanism for causing the upper tensioning means to be held in inoperative position for a predetermined number of operations as a new seam is started and a manually operated member for causing the 25 upper tensioning means to be held in inoperative position for an indefinite number of operations of the sewing mechanism.

6. A shoe lasting and sewing machine having, 30 in combination, upper tensioning means, sewing mechanism for securing a shoe upper and a sole together, a ratchet wheel driven in a step by step manner by the sewing mechanism, a cam connected to be driven by the ratchet wheel and means operated by the cam for preventing the upper tensioning means from operating as the sewing 35 mechanism starts a new seam and for causing the upper tensioning means to be rendered operative after a predetermined number of operations of the machine from the beginning of the 40 seam.

7. A shoe lasting and sewing machine having in combination, upper tensioning means, sewing mechanism for securing a shoe upper and a sole together, a ratchet wheel driven in a step by step 45 manner by the sewing mechanism, a cam connected to be driven by the ratchet wheel, means operated by the cam for causing the upper tensioning means to be held in inoperative position for a predetermined number of steps of the 50 ratchet wheel as the sewing mechanism starts a new seam, and a manually operated member for preventing rotation of the ratchet wheel for an indefinite number of operations of the sewing mechanism.

55 8. A shoe lasting and sewing machine having in combination, upper tensioning means, sewing mechanism for securing a shoe upper and a sole together, a ratchet wheel driven in a step by step manner by the sewing mechanism, a cam 60 connected to be driven by the ratchet wheel, means operated by the cam for causing the upper tensioning means to be held in inoperative position for a predetermined number of steps of the ratchet wheel as the sewing mechanism completes 65 a seam on a shoe, means for stopping rotation of the ratchet wheel for an indefinite number of operations of the sewing mechanism before the upper tensioning means is held inoperative and a manually operated member for causing the 70 ratchet wheel to continue its rotation after being stopped.

9. A shoe lasting and sewing machine having in combination, upper tensioning means, sewing mechanism for securing a shoe upper and a sole together, a ratchet wheel driven in a step 75

by step manner by the sewing mechanism, a cam connected to be driven by the ratchet wheel, means operated by the cam for causing the upper tensioning means to be held in inoperative position for a predetermined number of steps of the ratchet wheel as the sewing mechanism starts a new seam and before the seam is completed, means for holding the ratchet wheel against rotation for an indefinite number of operations of the sewing mechanism as the machine is started and for stopping rotation of the ratchet wheel before the upper tensioning means is held inoperative and a manually operated member for causing the ratchet wheel to start rotating at the beginning of a seam and to resume its rotation after being stopped by the stopping means. 15

10. A shoe lasting and sewing machine having in combination, upper tensioning means, sewing mechanism for securing a shoe upper and a sole together, a ratchet wheel driven in a step 20 by step manner by the sewing mechanism, a cam connected to be driven by the ratchet wheel, means operated by the cam for retaining the upper tensioning means in inoperative position for a predetermined number of steps of the 25 ratchet wheel as the sewing mechanism starts a new seam and before the seam is completed, a latch for holding the retaining means to prevent operation of the upper tensioning means and means actuated by the ratchet wheel for releasing the retaining means from the latch to permit the upper tensioning means to operate when the cam has continued its rotation.

11. A shoe lasting and sewing machine having in combination, upper tensioning means, 30 sewing mechanism for securing a shoe upper and a sole together, a ratchet wheel driven in a step by step manner by the sewing mechanism, a cam connected to be driven by the ratchet wheel, means operated by the cam for retaining 35 the upper tensioning means in inoperative position for a predetermined number of steps of the ratchet wheel as the sewing mechanism starts a new seam and before the seam is completed, a latch for holding the retaining means to prevent operation of the upper tensioning means, means actuated by the ratchet wheel for releasing the retaining means from the latch to permit the upper tensioning means to operate when the cam has continued its rotation, and an adjustable device actuated by the ratchet wheel for changing the number of operations of the sewing mechanism in which the upper tensioning means is retained in inoperative position at the beginning 40 of a new seam. 45

12. A shoe lasting and sewing machine having in combination, upper tensioning means, sewing mechanism for securing a shoe upper and a sole together, a ratchet wheel driven in a step by step manner by the sewing mechanism, a cam connected to be driven by the ratchet wheel, means operated by the cam for retaining the upper tensioning means in inoperative position for a predetermined number of steps of the ratchet wheel as the sewing mechanism starts a 60 new seam and before the seam is completed, a latch for holding the retaining means to prevent operation of the upper tensioning means, means actuated by the ratchet wheel for releasing the retaining means from the latch to permit the upper tensioning means to operate when the cam has continued its rotation, an adjustable device actuated by the ratchet wheel for changing the number of operations of the sewing mechanism in which the upper tensioning means is re- 65 70 75

- tained in inoperative position at the beginning of a new seam, means for stopping rotation of the ratchet wheel for an indefinite number of operations of the sewing mechanism before the upper tensioning means is held inoperative and a manually operated member for causing the ratchet wheel to resume its rotation after being stopped. 5
13. A shoe lasting and sewing machine having in combination, mechanism for progressively securing successive portions of a shoe upper and a sole together, an upper tensioning gripper acting in time with the securing mechanism to seize successive portions of the shoe upper preparatory to each securing operation, cam operated means 10 for preventing the gripper from seizing the upper during several of the first and final operations of the securing mechanism on a shoe, connections for causing the cam to be rotated by the securing mechanism and for stopping further 15 rotation of the cam at the end of a seam both before and after said operations of the securing mechanism in which the tensioning gripper is prevented from seizing the upper and a manually operated member for causing said connections to be effective in rotating the cam at the beginning of operations on a shoe and after the cam has 20 been stopped before the end of the operations. 25
14. A shoe lasting and sewing machine having in combination, mechanism for progressively securing successive portions of a shoe upper and a sole together, an upper tensioning gripper acting in time with the securing mechanism to seize successive portions of the shoe upper preparatory to each securing operation, cam operated means 30 for preventing the gripper from seizing the upper during certain of the operations of the securing mechanism and means operated with the cam for indicating to the operator the position in which the shoe should be presented to the 35 securing mechanism at all times during operation of the machine. 40
15. A shoe machine having in combination, mechanism for progressively securing portions of a shoe upper and a sole together, an upper tensioning gripper acting in time with the securing mechanism to seize successive portions of the shoe upper preparatory to each securing operation, levers for actuating the gripper to open and close in seizing the upper, connection between the 45 levers comprising a pair of aligned toggle links and a handle for moving the toggle links into and out of alignment to prevent at will the gripper from seizing the shoe upper. 50
16. A shoe machine having in combination, sewing mechanism for progressively securing successive portions of a shoe upper and a sole together, an upper tensioning gripper acting in time with the sewing mechanism to seize successive portions of the shoe upper preparatory to each sewing operation, means actuated by a predetermined number of operations of the sewing 55 mechanism to prevent the gripper from seizing the upper while sewing about the toe of the 60 shoe and a manually operated member for causing the upper tensioning gripper to be prevented from seizing the upper at the beginning and end portions of a seam. 5
17. A shoe machine having in combination, 10 sewing mechanism for progressively securing successive portions of a shoe upper and a sole together, an upper tensioning gripper acting in time with the sewing mechanism to seize successive portions of the shoe upper preparatory to each sewing operation, and means actuated after a predetermined number of operations of the sewing mechanism to prevent the gripper from seizing the upper while sewing about the toe portion of the shoe and along the beginning and 15 end portions of the seam. 15
18. A shoe machine having in combination, 20 sewing mechanism for progressively securing successive portions of a shoe upper and a sole together, an upper tensioning gripper acting in time with the sewing mechanism to seize successive portions of the shoe upper preparatory to each sewing operation, means automatically actuated by a predetermined number of operations of the sewing mechanism to prevent the gripper from seizing the upper while sewing about the toe of the shoe, a manually operated member for causing the upper tensioning gripper to be prevented from seizing the upper at the beginning and end portions of a seam and means 25 for visibly indicating to the operator at all times the number of operations of the sewing mechanism remaining before the gripper is automatically prevented from operating at the toe portion of the shoe. 30
19. A shoe lasting and sewing machine having, 35 in combination, stitch forming devices for progressively sewing successive portions of a shoe upper and sole together, an upper tensioning gripper acting in time with the stitch-forming 40 devices and during a portion only of the operation of sewing a shoe, and means for indicating to the operator the proper relative position in which the shoe should be presented to the stitch forming devices at all times during the sewing of a 45 shoe. 50
20. A shoe lasting and sewing machine having, 55 in combination, stitch forming devices for progressively sewing successive portions of a shoe upper and sole together, an upper tensioning gripper acting in time with the stitch forming 60 devices and during a portion only of the operation of sewing a shoe, a dial having an outline of a shoe, a pointer cooperating therewith to indicate to the operator by the point on the outline designated by the pointer the proper relative position in which the shoe should be presented to the stitch forming devices at all times during the sewing of a shoe, and means for actuating the dial. 60
